UNITED STATES PATENT OFFICE.

JOHN ROHDIEK, OF NEW YORK, N. Y.

ELECTRIC ENVELOP-SEALER.

1,378,721.

Specification of Letters Patent. Patented May 17, 1921.

Application filed August 6, 1920. Serial No. 401,744.

To all whom it may concern:

Be it known that I, JOHN ROHDIEK, a citizen of United States, residing at New York, in the county of New York and State of New York, have invented new and useful Improvements in Electric Envelop-Sealers, of which the following is a specification.

This invention relates to envelop sealers and has for its object the provision of an electrically operated device for sealing the flaps of envelopes and also for affixing stamps thereon.

An important object is the provision of a device of this character including a plurality of drive rollers moving beneath a cover plate with which they coöperate for pressing the flaps of envelopes into position and for also pressing stamps into place, the cover having associated therewith an electric heater for drying the adhesive upon the flaps and stamps and this heater being automatically cut into circuit when the cover is closed and simultaneously with the operation of the motor which drives the rollers.

An additional object is the provision of a device of this character which will be simple and inexpensive in manufacture, highly efficient and easy to use, durable in service, and a general improvement in the art.

With the above and other objects and advantages in view, the invention consists in the details of construction to be hereinafter more fully described and claimed and illustrated in the accompanying drawings in which—

Figure 1 is a plan view of my device,

Fig. 2 is a side elevation with the cover in closed position,

Fig. 3 is a longitudinal sectional view with the cover closed,

Fig. 4 is a plan view with the cover open,

Fig. 5 is a sectional view on the line 5—5 of Fig. 1,

Fig. 6 is a cross sectional view, taken on the line 6—6 of Fig. 1, and

Fig. 7 is a diagrammatic view of the electric wiring.

Referring more particularly to the drawings, the numeral 10 designates the base of the machine which is formed of any suitable material and size but which is rectangular in shape. Mounted upon this base are spaced side bars 11 which may conveniently be short sections of angle iron and journaled between these side bars are rollers 12 of uni-

form size and which carry gears 13 between which are located intermediate idle pinions 14, the purpose of which is to insure rotation of all the rollers 12 in the same direction at the same speed.

Located adjacent the gear 13 on one of the end rollers is a drive pinion 15 carried by the shaft 16 of an electric motor 17 which has one terminal connected with a suitable source of current A and which has its other terminal connected with the stationary contact 18 suitably mounted upon the base. The numeral 17^a designates a housing for the gearing.

Secured upon the base is the lower portion 19 of a casing which incloses the mechanism above described and which further includes a hinged cover 20 having a suitable handle 21 and this cover is provided at one end 75 with an entrance opening 22 and at its opposite end with a discharge opening 23. The casing is preferably provided adjacent these openings with platforms 24 and 25, respectively, onto the former of which envelopes to 80 be sealed may be placed and the latter of which serves as a support for the sealed envelopes.

Carried by the cover 20 is a heating coil 26 which has one terminal connected with the source of current A and which has its other terminal connected with a contact 27 carried by and insulated from the cover. The contact 27 is so arranged that when the cover is closed it will engage with the contact 18 so that when the cover is in such closed position current will flow from the source through the heating coil 26 and through the motor 17. This will result in heating of the cover and also in rotation of the rollers 12. A plate 28 is disposed between the rollers and the heater.

In the use of the device when it is desired to seal envelopes or to affix stamps thereon it is first necessary to moisten the flap and to apply the stamp, after which the envelop is placed upon the platform 24 and slid into the entrance opening 22 whereupon the moving rollers 12 will carry the envelop along the casing in engagement with the plate 28 which will result in pressing of the flap and stamp firmly into position. Owing to the energization of the heating coil 26, the plate 28 will be very efficiently heated and this will result in drying of the adhesive upon the flap and stamp so that when the envelop is discharged through the opening

23 onto the platform 25 the mucilage or other adhesive will be dry and the envelop will be in condition for mailing. When the cover is opened the contacts 27 and 18 5 will be disengaged and the circuit will be broken through the heating coil and also through the motor so that the device will automatically become inoperative.

From the foregoing description and a 10 study of the drawings it will be apparent that I have thus provided a simply constructed and easily operated envelop sealing device and stamp affixer which will not only press the flap and stamp firmly into position but will also thoroughly dry the adhesive so that subsequent loosening will be prevented.

20 While I have shown and described the preferred embodiment of my invention, it is of course to be understood that I reserve the right to make such changes in the form, construction, and arrangement of parts as will not depart from the spirit of the invention or the scope of the subjoined claims.

25 Having thus described my invention, I claim:

1. A device of the character described comprising a casing, a plurality of rollers journaled therein, a motor for driving said

rollers simultaneously in the same direction, 30 a cover for said casing, a plate within the cover, coöperating with said rollers whereby to press against an envelop disposed between the rollers and the cover, and means for heating said cover comprising an electric 35 heater carried thereby, and means for simultaneously energizing said heater and said motor.

2. A device of the character described comprising a casing, a plurality of rollers 40 journaled therein, a motor for driving said rollers simultaneously in the same direction, a cover for said casing including a plate, co-operating with said rollers whereby to press against an envelop disposed between the 45 rollers and the cover, and means for heating said plate comprising an electric heating coil carried by the cover, a contact carried by the cover and connected with said coil, said coil being connected with a source of 50 current, said motor being likewise connected with said source of current, and a contact connected with said motor and engageable by said first named contact whereby when the cover is closed the motor and coil will be 55 simultaneously energized.

In testimony whereof I affix my signature.
JOHN ROHDIEK.
